UNITED STATES PATENT OFFICE.

LEO J. SPAEDER, OF ERIE, PENNSYLVANIA.

PAPER BOARD.

Application filed October 28, 1924. Serial No. 746,353.

To all whom it may concern:

Be it known that I, LEO J. SPAEDER, a citizen of the United States, residing at Erie, in the county of Erie and State of Pennsylvania, have invented new and useful Improvements in Paper Boards, of which the following is a specification.

This invention is designed to form flat boards, particularly boards to be used as checker boards. Such boards have usually been formed of wood but it has been sometimes attempted to form them from solid paper board stock. The wood is rather expensive and the solid paper board stock is inclined to warp and lack rigidity. In carrying out my invention I use a flat corrugated paper stock having a corrugated core with flat sides and cover this completely with a cover strip or glazed paper of sufficient stiffness to make rigid, square-turned edges for this corrugated stock. Thus a board of sufficient rigidity to form a checker board without the box flanges can be made and there is no tendency to warp and the edges are given an appearance of solidity and thickness that adds very much its appearance.

The invention is illustrated in the accompanying drawings as follows:—

Fig. 1 shows a perspective view of the checker board.

Fig. 1^a a fragment of a checker board face.

Fig. 2 a section on the line 2—2 in Fig. 1.

Fig. 3 a plan view of the cover blank.

Fig. 4 an enlarged sectional view of an edge of the board.

The corrugated board is made up of the central corrugated core 1 with the flat sides 2. The boards are cut to the proper size. This gives the unsightly and readily crushed edges. The cover paper has one face 3. Immediately adjacent to this face are the edges 4 which are of a width corresponding to the thickness of the corrugated board. The cover blank is scored on the lines 5—5 at each margin of the face forming the board edge. Flaps 6 are formed on three of the sides in continuation of the strips 4 and an inside cover face 7 is formed in continuation of the remaining

side. This blank is placed on the outer surface of the board, the parts 4 adjacent to the flaps 6 are carried up along the edges of the board and the flaps 6 folded in and pasted on the face of the board. The part 4 adjacent to the face 7 is carried up along its edge and the part 7 pasted down on the remaining side of the board. Thus the board is entirely encased with a cover of sufficient stiffness and thickness, usually a glazed stock, and the square-turned rigid corners are formed, closing, bracing and giving rigidity to the edges of the corrugated board so that the board as a whole has the rigidity and sightliness of a wood board, the corrugated board preventing the tendency to warp and giving rigidity, the cover board giving rigidity and squareness of contour at the edges. The two boards are hinged together by a hinge strip 8 which is secured to two adjacent edges and ordinarily extends at 9 along the faces.

What I claim as new is:—

1. A flat paper board formed of corrugated paper with a corrugated core and flat sides, and a cover of paper folded around the corrugated board with square-turned corners forming a flat edge of the thickness of the corrugated board, said cover board being of a stiffness to give rigidity to the edge.

2. A flat paper board formed of corrugated paper with a corrugated core and flat sides, and a cover of paper folded around the corrugated board with square-turned corners forming a flat edge of the thickness of the corrugated board, said cover being of a stiffness to give rigidity to the edge, said cover board being scored at the margins of the edges.

3. A flat paper board formed of corrugated paper with a corrugated core and flat sides, and a cover of paper folded around the corrugated board with square-turned corners forming a flat edge of the thickness of the corrugated board, said cover board being of a stiffness to give rigidity to the edge, said cover having united opposing covering faces of the dimensions of the corrugated board.

4. A checker board formed of flat sec-

tions, each section formed of a flat paper board having a corrugated core with flat sides and a cover of paper folded around the corrugated board with square-turned corners forming a flat edge of the thickness of the corrugated board, said cover board being of a stiffness to give rigidity to the

edge, the sections being hinged by a strip secured to the opposing edges of the flat board.

In testimony whereof I have hereunto set my hand.

LEO J. SPAEDER.
